UNITED STATES PATENT OFFICE.

BRYAN P. JOYCE, OF DAVENPORT, IOWA.

ADJUSTABLE COUNTERPOISE.

Application filed April 7, 1925. Serial No. 21,396.

The subject of this invention is an adjustable counterpoise intended primarily for use with heavy ordnance but not restricted to such use as it may be employed as a component part of any object mounted for oscillation.

The principal object of the present invention is the provision of an adjusting device for increasing or decreasing the effective crank arm and the volume of the counterpoise to compensate for changes in its moment due to variations in pressure as effected by the differences between existing temperatures and the temperature at which the counterpoise is loaded.

In the present disclosure only one trunnion of the oscillatory body, with the counterpoise attached thereto, is illustrated and described as the structure connected to the other trunnion would be a duplicate.

To these and other ends, my invention consists in the construction, arrangement, and combination of elements, described hereinafter and pointed out in the claims forming a part of this specification.

A practical embodiment of the invention is illustrated in the accompanying drawing, wherein:

Fig. 1 is a view in side elevation of a counterpoise constructed in accordance with the invention, a fragment of the side plate of a top carriage to which the counterpoise is attached being shown;

Fig. 2 is a fragmentary plan view of the arm connecting the trunnions of the counterpoise and the oscillatory body; and

Fig. 3 is a detail sectional view on the line 3—3 of Fig 1.

Referring to the drawing by numerals of reference:

The fragment of a top carriage side plate is designated by the numeral 5 in which plate is journaled a trunnion 6 supporting oscillatory parts of a gun. Rigidly fixed to the trunnion by means of the keys 7 is a suitable crank arm preferably comprising a single web 8 formed with a frame 9 having a closed end 10 and strengthened by a top plate 11.

Mounted in the opening of the frame 9 of

the arm is a pneumatic counterpoise casing 12 within which is a reciprocal element 13 conveniently a plunger or piston having an end 14, herein shown hemi-spherical, seated in a recess formed in the bracket 15. A valve 16 in the casing is provided for admitting fluid under pressure, the pressure and temperature at loading being predetermined.

The casing 12 is encircled by a trunnion band 17 carrying trunnions 18 whereby the counterpoise is pivotally mounted, preferably in ball bearings, in the sides of a carriage 19 slidably mounted between a pair of seats 20 on the inner side of each of the side walls of the frame 9. The carriage is formed with a closed end 21, the purpose of which will presently appear and may, to facilitate assembly, also include trunnion caps 22. The carriage 19 is adapted to be reciprocated to vary the distance between the axis of oscillation and the counterpoise trunnions thereby increasing or decreasing the effective length of the crank arm and the volume of the counterpoise with respect to a predetermined zero of initial loading. This adjustment is necessary in pneumatic counterpoises to compensate for variations in its moment due to changes between the temperature at loading over the temperature when in use.

Any suitable means for reciprocating the carriage may be provided, that herein shown consisting of a screw rod 23 journaled in the closed end 10 of the frame and held against longitudinal movement in either direction by its head 24 and a collar 25. The rod threads into the end 21 of the carriage so that the carriage is reciprocated upon rotation of the rod.

For the purpose of indicating the displacement of the carriage with respect to a zero setting, a slide 26 graduated, plus and minus, in values of degrees of temperature is secured to one of the counterpoise trunnions by a pin 27, the slide moving in a groove 28 and the pin accommodated by a slot 29, both in the outer side wall of the crank arm frame 9. A reference mark 30 is provided on the frame against which the

scale may be read. The counterpoise is loaded to a predetermined pressure at a predetermined temperature with the zero of the scale and the reference mark in coincidence.

5 Attention is directed to the fact that in the present invention the effective length of the crank arm is obtained by adjustment and is not automatically increased during 10 elevation of the oscillatory movement, as described in my Patent No. 1,503,589.

In the present instance it will be understood that self-contained means may be provided within the counterpoise to compensate for divergence between the moment 15 curves of the counterpoise and the oscillatory body as the latter is elevated above 45°.

While in the foregoing there has been illustrated and described such arrangement 20 and combination of elements, as constitute the preferred embodiment of the invention, it is nevertheless desired to emphasize the fact that interpretation of the invention should only be conclusive when made in the 25 light of the subjoined claims.

I claim:

1. The combination with a support having a bracket, of a trunnion journaled in the support, a crank fixed to the trunnion and 30 formed with a frame, a pneumatic counterpoise casing disposed within the frame, a plunger working in the casing and pivoted in the bracket, a trunnion band fast on the casing, trunnions on the band, a carriage 35 slidably mounted on the inner side walls of the frame and receiving the counterpoise trunnions, a rod journaled in the closed end of the frame and threaded in the carriage whereby to reciprocate the carriage and vary 40 the effective arm and volume of the counterpoise, a scale graduated in degrees temperature and secured to one of the counterpoise trunnions to partake of its adjusting movement, and a reference on the frame against 45 which the scale may be read.

2. The combination with a support having a bracket, of a trunnion journaled in the support, a crank fixed to the trunnion and 50 formed with a frame, a pneumatic counterpoise casing disposed within the frame, a plunger working in the casing and pivoted in the bracket, a trunnion band fast on the casing, trunnions on the band, a carriage 55 slidably mounted on the inner side walls of the frame and receiving the counterpoise trunnions, means for reciprocating the carriage to vary the effective arm and volume of the counterpoise, a scale graduated in degrees temperature and secured to 60 one of the counterpoise trunnions to partake of its adjusting movement, and a reference on the frame against which the scale may be read.

3. The combination with a support having 65 a bracket, of a trunnion journaled in

the support, a crank fixed to the trunnion and having an open portion, a pneumatic counterpoise casing disposed in the open portion, a plunger working in the casing and pivoted in the bracket, trunnions fast 70 on the casing, a carriage slidably mounted on the crank and receiving the counterpoise trunnions, means for reciprocating the carriage to vary the effective arm and volume of the counterpoise, a scale graduated in 75 degrees temperature and secured to one of the counterpoise trunnions to partake of its adjusting movement, and a reference against which the scale may be read.

4. The combination with a support having 80 a bracket, of a trunnion journaled in the support, a crank fixed to the trunnion, a carriage slidably mounted on the crank, a counterpoise trunnioned in the carriage and having a plunger pivoted in the bracket, 85 means for reciprocating the carriage to adjust the volume and effective arm of the counterpoise, and means for indicating the amount of adjustment.

5. The combination with a support having 90 a bracket, of a trunnion journaled in the support, a crank fixed to the trunnion, a carriage slidably mounted on the crank, a counterpoise trunnioned in the carriage and having a plunger pivoted in the bracket, 95 and means for reciprocating the carriage to displace the counterpoise trunnions.

6. The combination with a support, of a trunnion journaled therein, a crank fixed 100 to the trunnion, a counterpoise having trunnions movably supported from the crank, means for maintaining said trunnions in fixed position, means whereby they may be displaced to adjust the volume and effective arm of the counterpoise, and means for indicating the amount of adjustment.

7. The combination with a support, of a trunnion journaled therein, a crank fixed 110 to the trunnion, a counterpoise having trunnions movably supported from the crank, means for maintaining said trunnions in fixed position, and means whereby they may be displaced to adjust the volume and effective arm of the counterpoise.

8. The combination with a support, of a trunnion journaled therein, a crank fixed 115 to the trunnion, a counterpoise, means for supporting the counterpoise from the crank, means for changing the point of support, and means for indicating the amount of 120 change.

9. The combination with a support, of a trunnion journaled therein, a crank fixed 125 to the trunnion, a counterpoise, means for supporting the counterpoise from the crank, and means for changing the point of support.

10. The combination with a trunnion, of a crank fixed thereto, a counterpoise adapted 130 to be supported by the crank, means where-

by the point of support may be changed to vary the arm and volume of the counterpoise, and means for indicating the amount of change.

5 11. The combination with a trunnion, of a crank fixed thereto, a counterpoise adapted to be supported by the crank, and means whereby the point of support may be

changed to vary the effective arm and volume of the counterpoise.

12. The combination with a pivoted body, of a crank connected thereto, a counterpoise adapted to be supported by the crank and means whereby the point of support may be changed.

BRYAN P. JOYCE.
